UNITED STATES PATENT OFFICE.

WILLIAM FRARY, OF CLINTON, MICHIGAN.

IMPROVEMENT IN SAD-IRON HEATERS.

Specification forming part of Letters Patent No. 149,582, dated April 14, 1874; application filed March 13, 1874.

To all whom it may concern:

Be it known that I, WILLIAM FRARY, of Clinton, in the county of Lenawee and State of Michigan, have invented a new and useful Improvement in Sad-Iron Heaters; and I do hereby declare that the following is a full, clear, and exact description thereof, reference being had to the accompanying drawings, making part of this specification, in which—

Figure 1 is a perspective view of my sad-iron heater as placed upon the top of a stove. Fig. 2 is a longitudinal section of the same, and Fig. 3 a transverse section of the same.

The nature of my improvement in sad-iron heaters consists, first, in the combination of a horizontal slotted diaphragm with the cover or case, which, as usual, is constructed without a bottom, and is slotted through its top and through its front side, to admit the body and handle of the sad-iron; second, in a slotted diaphragm or partition, which is self-adjusting, in combination with the slotted and perforated case; third, in the combination of a certain construction of supporting and releasing rods with the partition of the sad-iron heater. The object of my improvement is to form a chamber or air-space between the body of the sad-iron and the top of the case, and thereby protect the handle as much as possible from the influence of the heater which is employed to heat the body of the sad-iron; and, while this is the case, another object of my improvement is to have the space in which the body of the sad-iron is heated of no greater depth than the thickness of the sad-iron, and thereby compel the heat which is employed to heat the sad-iron to impinge directly upon, and expend itself to a very great degree upon, the sad-iron below the air-chamber in which the handle of the iron is mainly placed. The third object is to prevent a casual displacement of the supporting-rods of the partition, and, at the same time, have them self-fastening.

A is the case or cover, made of sheet metal, wire-bound, and, in form and construction, similar to an ordinary flaring dripping-pan when the same is inverted. The best proportions for depth and width of this case are, one and a half to two inches deep, and eight to twelve inches wide. The length will vary according to the number of irons it is required

to heat. These proportions may be varied as circumstances require. This case or cover has one or more openings, B, through its front side, large enough to admit the body portion *a* of a flat-iron through it, and these openings are intersected at the middle of their length—at top—by a narrow slot or slots, B', which are cut down through the top or front side of the cover, as shown. The slots B are provided in order to admit the handles *a'* of the iron through them, and extend back through the top a proper distance to permit the body of the sad-iron to be placed entirely under the top of the case, as illustrated in Figs. 1 and 3 of the drawings. C is a horizontal partition or diaphragm, placed within the case, below the top thereof. This partition is set upon rods *c c*, which pass through the cover from side to side. These rods alone sustain the partition in its position. Their front ends are formed with a ring-handle, and their rear ends are made with a spiral or cork-screw twist, and these latter ends are screwed through oblong slots *g* in the rear side of the cover. When the rods are inserted properly, they cannot get out of position until turned and drawn back by the manager of the heater. The partition is slotted in a corresponding manner with the top of the cover, as shown at *d*, and, at the front end of the slot, the corners are cut off, so as to form flaring entrances for the handles of the sad-irons.

Thus arranged, the partition forms an air space or chamber, *f*, between its top side and the under side of the case; and, further, it is free to rise and fall within the case whenever sad-irons of greater thickness than the space between its under side and the top of the stove D, upon which the cover is placed, are introduced under the partition. This adjustability adapts the apparatus to irons of varying thickness, and also insures a close fit upon irons which are just the thickness that the apparatus is constructed to receive below its partition.

I am aware that sad-iron heaters are not a new thing, broadly. I also am aware that slotted and perforated covers or cases are not new; and, likewise, that the handle has been partially isolated from the heat within the case by hinged pieces; but I believe it is new to construct a sad-iron heater with the air-chamber

above the diaphragm, and to have the diaphragm self-adjusting and always fitting down or riding upon the top of the body portion of the irons, as I have set forth.

My improvement greatly reduces the cost of ordinary sad-iron heaters, and gives greater convenience to those using the heater, while the heating of irons is greatly facilitated with a given consumption of fuel.

What I claim as my invention, and desire to secure by Letters Patent, is—

1. The sad-iron heater constructed with the partition or diaphragm C, substantially in the

manner and for the purpose herein described and shown.

2. The partition or diaphragm C, supported upon rods, and made self-adjustable, substantially as herein described.

3. The combination of the rods having a spiral twist on one end and a ring on the other with the diaphragm of the sad-iron heater, as described and shown.

WILLIAM FRARY.
